UNITED STATES PATENT OFFICE.

ALBERT LATHAM, OF BEVERLY, MASSACHUSETTS, ASSIGNOR TO UNITED SHOE MACHINERY CORPORATION, OF PATERSON, NEW JERSEY, A CORPORATION OF NEW JERSEY.

SKIVING-MACHINE.

1,301,283.

Specification of Letters Patent. Patented Apr. 22, 1919.

Application filed February 12, 1918. Serial No. 216,734.

To all whom it may concern:

Be it known that I, ALBERT LATHAM, a citizen of the United States, residing at Beverly, in the county of Essex and State of Massachusetts, have invented certain new and useful Improvements in Skiving-Machines; and I do hereby declare the following to be a full, clear, and exact description of the invention, such as will enable others skilled in the art to which it appertains to make and use the same.

The present invention relates to skiving machines and more particularly to machines of this character employed for operation upon the uppers of boots and shoes.

Machines of this type are employed primarily for skiving or beveling the marginal portions of shoe uppers and as these uppers are composed of thin flexible material it is a matter of some considerable difficulty to produce the even, uniform bevel edge which is desired.

The object of the invention is to produce a machine which shall perform the requisite operations with extreme accuracy and maintain this accuracy of operation through long continued use. With this object in view, the several features of the invention consist in certain new and useful features of construction, together with combinations and arrangements of parts operating in a novel manner, all the advantages of which will be obvious to those skilled in the art from the following description.

In the accompanying drawings illustrating the preferred form of the invention, Figure 1 represents a front elevation of a machine embodying the several features of the invention; Fig. 2 is an end elevation of the machine shown in Fig. 1; Fig. 3 is a top plan view of the machine shown in Fig. 1; Fig. 4 is a view showing the hinged head of the machine thrown back and illustrating a bottom plan view of the contained mechanism; Fig. 5 is a detail illustrating a cross section of the feed roll and operating mechanism; Fig. 6 is a detail showing a cross section of the feed roll drive taken upon the line 6—6 of Fig. 5; Fig. 7 is a detail showing a section of the feed roll support taken upon the line 7—7 of Fig. 2; and Figs. 8 and 9 are details showing a cross section upon the line 8—8 of Fig. 3 and illustrating the latch in two different operative positions.

The skiving machine shown in the illustrated embodiment of the invention com-

prises a rotary tubular skiving knife indicated at 10, a gaging member 11, and a presser and feed roll 12 which co-operates with the member 11 to guide and feed the work to the edge of the knife. The gage member 11 is detachably secured to a slide 14 having a stem 15 slidingly received in a vertical slot 16 formed in an overhanging arm 17. The vertical position of the gage member is controlled by a stop screw 18 threadedly mounted in the arm and arranged to bear upon the upper end of the stem 15. The latter is yieldingly maintained in contact with the screw by a spring 19 supported at its lower end upon a cross bar 20 secured to the arm 17 and received in a slot formed in the stem. The angle of the bevel formed by the skiving knife is varied in the usual manner by adjusting the gage member transversely of the knife so that the curved face 21 of the member intersects the knife edge at a different point. This adjustment of the gage member is facilitated through the provision of a stem 23 passing loosely through the gage member and slide 14 and having its end threaded in a nut 24 received in a recess formed in the back of the slide. An arm 25, secured to the front end of the stem, serves as a means for operating the stem to clamp the gage member to the head. The construction is so designed that approximately a quarter rotation of the stem serves to clamp the gage member to the head. The nut 24 is provided with a fluted edge 26, as shown clearly in Fig. 2 of the drawings, which is engaged by a threaded pin 27 to prevent the nut from turning with the stem 23. By removing the pin 27, however, the nut may be manipulated so that the clamping position of the arm 25 is that shown in the drawings in which the arm extends substantially vertically and does not interfere with the free operation of the machine. A movement of the arm from this position into a position in engagement with the stop pin 29 serves to release the gage member and permits it to be adjusted transversely in the dove-tailed ways formed in the slide 14.

The feed roll 12, as is usual in machines of this type, has capacity for a bodily yielding movement toward and from the knife edge, a tilting movement about the end of the feed roll opposite the point of operation of the knife, and a circumferential adjustment relative to the knife to vary the work-

ing surface of the feed roll. During the operation of the machine the feed roll is continuously rotated to feed the work to the knife edge and it is essential that this mechanism shall serve to drive the roll at a uniform speed and in any position of the roll. The feed roll 12 is secured to a shaft 31 journaled at opposite ends in a head 33 pivoted upon a carrier 34 at 35. The feed roll 10 is normally positioned, as shown in the drawings, with the surface concentric with the knife edge through the provision of co-operating stop faces 37 and 38 formed upon the carrier and head, respectively, and is 15 permitted to yield from this position about the pivot 35 through the provision of a spring 39 received in a recess 40 formed in the carrier and positioned beneath a flange 41 formed upon the head. The pressure of 20 the spring may be regulated by a plug 42 threaded in the carrier and upon which the spring 39 rests. The carrier 34 is pivoted upon a stud 43 which is aligned with the axis of the knife and is rocked about this stud 25 shaft by an arm 45 having a spring pressed detent 46 in its free end which engages with one of a series of recesses 47 to retain the arm in adjusted position. The purpose of 30 this construction is to vary the position of the feed roll beneath the gage member so that if any portion of the surface is rendered inefficient by the accumulation of material thereon, another portion of the surface becomes available. The stud shaft 43 35 is mounted in a frame 50 which is fulcrumed upon a shaft 52 supported at its opposite ends in the frame of the machine. The frame 50 is provided with a depending tail 53, as shown in Figs. 2 and 7 of the drawings, which engages at its lower end with an 40 eccentric stud 54 journaled in the machine frame and having a knurled head 55 upon the outer end. This stud extends parallel to the shaft 52 and through its engagement 45 with the tail 53 determines the angular position of the frame 50 and the feed roll 12 carried thereby. The tail 53 is yieldingly retained in engagement with the stud by a spring 55 received within a hollow boss 56 50 formed upon the machine frame and surrounding a stem 57 having a ball-shaped end 58 which is connected to the tail 53 through a correspondingly shaped socket formed in the tail. The pressure of the spring is 55 regulated by a cap 60 threadedly connected to the end of the stem 57 and having an annular shoulder 61 against which the spring 55 bears. The cap is provided with the usual hexagonal head 62 for the reception 60 of a wrench or other instrumentality. With this construction the feed roll is initially adjusted to bring the surface of the roll into close proximity with the knife edge and is yieldingly retained in this position. During 65 the operation of the machine the feed

roll is permitted to yield bodily away from the knife edge or to tip angularly about one end to accommodate material of varying thickness. After the initial adjustment of the feed roll has been secured the eccentric stud 54 is clamped in position by a locking member 64 threaded in the machine frame and having a pointed end which engages with an annular groove 65 formed in the stud 54, as shown clearly in Fig. 6. A transverse adjustment of the feed roll to align the shaft 43 with the knife shaft is secured by bodily adjusting the frame 50 and the parts carried thereby. As shown in Figs. 2 and 3, the frame 50 is held against longitudinal movement relative to the shaft 52 by a collar 67 pinned to the shaft and received in a slot formed in the hub of the frame. The shaft 52 is threaded into the machine frame at 68 and is provided with a lock nut 69 to retain the shaft in adjusted position. With this construction in case the feed roll is not initially positioned so that the surface is concentric with the knife edge the threaded connection of the shaft 52 with the machine frame is utilized to adjust the frame 50 and the feed roll carried thereby transversely with relation to the skiving knife after which the lock nut 69 is tightened to clamp the parts in adjusted position. This adjustment, as well as the adjustment secured by the eccentric stud 54, is intended merely for convenience in assembling the machine to locate the feed roll in the proper operative relation to the skiving knife. 100

The head of the machine is conveniently made in two parts 70 and 71 hinged at 73. The part 71 carries the feed roll and operating mechanism and is designed to expose the interior of the knife when it is swung away from the part 70 about the hinges 73. The feed roll drive shaft 74 illustrated in Figs. 3 and 4, is journaled in the base portion 70 of the machine frame and is provided with the usual pulley 75 which is operated from the knife shaft 76 through a drive pulley 77 and connecting belt 78 at the back of the machine frame. The front end of the feed roll shaft 74 is provided with a clutch face indicated at 80 which engages with and drives a correspondingly shaped clutch face 81 formed upon the end of a shaft 82 journaled in the swinging portion 71 of the base. When the base is closed the two shafts are positioned in alignment with one another and through the engagement of the clutch faces 80 and 81 are rotated as one. The shaft 82 operates a transverse shaft 84 through a worm 85 and gear 86 secured, respectively, to the shafts 82 and 84. The shaft 84 is secured against endwise movement in the base portion 71 through a collar 87 and thrust bearing 88 and is provided upon its inner end with a sleeve 90 which is journaled within 110

120

125

130

the machine frame. A sliding block 92 is splined within the sleeve 90 and is connected to the shaft 31 of the feed roll by a rod 94 having ball-shaped ends 95 connected to the block and shaft 31, respectively, by transverse pins 96 received in longitudinal slots 97 formed in the ball ends. This construction provides a simple and efficient mechanism for communicating the rotary motion 10 of the feed roll drive shaft to the feed roll in any position of the latter, the block 92 sliding within the sleeve 90 and the connecting rod 94 assuming an angular position dependent upon the varying positions of 15 the feed roll. A longitudinal play of the connecting rod 94 is prevented through the provision of a washer 100 of felt or other suitable material which is received within the end of the block 92 in a position to engage with the ball end 95 of the rod.

As stated previously, the interior of the skiving knife is conveniently made accessible by swinging back the portion 71 of the head which carries the feed roll and 20 connected parts. By exposing the interior of the knife in this manner any accumulation of skivings or other material may be readily removed without stopping the machine. It is advisable, however, to insure that the feed 25 roll does not engage with the knife edge when the portion 71 of the head is opened or closed. To this end connected mechanism is provided for locking the two portions 30 70 and 71 of the head together and for 35 automatically depressing the feed roll when the two portions are unlocked to permit opening of the head. A latch arm 105 is secured to a shaft 106 outside of the machine frame. The shaft 106 is provided with 40 a cam 108 on its inner end, as shown in Figs. 1 and 3, which engages with the lower end of a depending arm 110 secured to the rocking frame 50. When the latch arm 105 rests against the stop pin 111 to 45 lock the two portions of the head together, the feed roll is supported in the normal operative position in close proximity to the knife edge but when the latch arm is swung into position against the pin 50 175 to unlock the two portions of the head the cam 108 rocks the arm 110 and frame 50 to depress the feed roll. The latch arm is provided with a hub 107 which has an interrupted flange 109 adapted to engage a 55 lug 176 formed upon a stationary locking bar 177. When the arm rests against the pin 175 the opening in the flange is aligned with the lug 176 to permit the two portions of the head to be closed and when the latch 60 arm is swung into a horizontal position the flange which is slightly eccentric engages the lug and draws the two parts of the head tightly together as shown in Figs. 8 and 9.

The skiving knife is of the built-up type in 65 which a thin, flexible knife blade is clamped to

an external holder through suitable clamping mechanism actuated from the opposite end of the knife shaft. As shown in Figs. 1 and 4 of the drawings, the knife blade 114 is clamped within a holder 115 and the 70 clamping and adjusting mechanism is actuated from the opposite end of the shaft through suitable hand wheels 116 and 117. The specific form of the skiving knife embodied in this machine is that disclosed in 75 the co-pending application of applicant filed of even date herewith.

It is of extreme importance that the knife blade shall be accurately ground upon opposite sides in order that all parts of the 80 cutting edge of the knife shall lie exactly in the true circle of rotation of the knife. It is furthermore desirable that a keen cutting edge shall be constantly maintained without undue grinding of the knife blade, 85 thus conserving the effective life of the blade and increasing the efficiency. According to the present invention the opposite surfaces of the knife blade when positioned in the machine are engaged by rotary grinding 90 members to form a cutting edge which is not affected by irregularities in the thickness of the blade. The outer grinding member is positively held in engagement with the surface of the knife and the inner grinding 95 member is yieldingly retained in engagement with the knife, the movement of the member toward the knife being limited by an adjustable stop. According to the usual practice the stop for the inner grinder is 100 adjusted to form a more or less continuous engagement of the grinding member with the knife blade which gradually grinds away any bur or inequalities which may be present in the surface of the blade. As illustrated in Fig. 4 of the drawings the outer surface of the knife blade is engaged by a grinding member which comprises an annular ring 112 of abrasive material secured to a disk 118 supported for rotation in a plane 105 inclined to that of the knife shaft in order that the outer surface of the blade shall be ground upon a bevel. The disk 112 is mounted upon the inner end of a shaft 119 journaled in a bearing yoke 120 adjustably 110 secured to the end of an arm 121. The bearing yoke is provided with a projection 122 having a curved slot 123 which receives a threaded fastening 124 secured to the arm 121, and permits an angular adjustment of 115 the bearing yoke and grinding member carried thereby about an axis passing substantially through the point of contact between the grinding disk and knife blade. The arm 121 is pivoted at 125 to a lug 126 formed upon the portion 70 of the machine frame and is actuated to move the grinding member toward and from the knife blade by a rod 128 which passes through the side 120 of the head and is provided with an actuat- 110

ing knob 130 upon its outer end. The inner end of the rod 128 threadedly engages with a nut 131 swiveled within a boss 132 formed upon the arm 121. In order to gage the movements of the grinding disk an indicator 133 is clamped upon the hub of the knob 130 and the latter is provided with a serrated inner face engaged by a spring pressed detent 134 all as shown in Fig. 3.

10 The grinding member is rotated during the operation of the machine from the knife shaft 76 through a drive pulley 136 secured to the knife shaft which operates the member through a belt 137 and driven pulley 138 secured to the shaft 119. The belt 137 passes around guide pulleys 140 journaled upon the outer end of an arm 141 which is pivoted to the machine frame at 142. The arm 141 may be moved to regulate the tension upon 15 the belt or stop the rotation of the grinding disk through an adjusting screw 143 threaded in the side of the machine frame and engaging at its inner end with a short arm 144 projecting from the arm 141. With this 20 construction the grinding operation may be halted without disturbing the adjustment of the grinding disk by merely manipulating the screw 143 to relieve the tension upon the driving belt. The inner surface of the 25 knife blade is engaged by the face of the grinding disk 150 which is rotated through contact with the moving knife blade and is adjusted to regulate the grinding action through knurled members 151 and 152. This 30 grinding disk is supported in a head 153 adjustably secured to the outside of the machine frame in such a manner that the position of the grinding member may be regulated to cause the face of the member to 35 engage with the moving knife blade at two points. This construction is disclosed in the pending application of applicant Serial No. 45,402, filed August 13, 1915.

In order to afford convenient access to the 40 interior of the head as a whole the latter is hinged at 155 upon a base member 156 and may be swung back bodily as shown in Fig. 4.

While it is preferred to employ the specific 45 construction and arrangement of parts shown and described, it will be understood that this construction and arrangement is not essential except so far as specified in the claims, and may be changed or modified 50 without departing from the broader features of the invention.

The invention having been described, what is claimed is:

1. A skiving machine having, in combination, 60 a tubular skiving knife, a gage member upon one side of the knife, a feed roll upon the opposite side of the knife, a pivoted carrier supporting the feed roll to permit a circumferential adjustment of the roll relative 65 to the knife, and means for supporting the

carrier having provision for adjustment of the carrier and feed roll transversely of the knife.

2. A skiving machine having, in combination, 70 a tubular skiving knife, a gage member upon one side of the knife, a feed roll upon the opposite side of the knife, a pivoted carrier for the feed roll, a frame supporting the carrier, a shaft extending transversely of the knife and upon which the frame is supported, and means for moving the shaft longitudinally to secure a bodily adjustment of the carrier and feed roll transversely of the knife.

3. A skiving machine comprising a skiving 80 knife, a feed roll and coöperating gage member positioned upon opposite sides of the knife, means for supporting the feed roll in a predetermined operative relation to the knife edge, and means for varying the predetermined position of the feed roll including a rotary eccentric member.

4. A skiving machine comprising a feed 90 roll, a pivoted frame supporting the feed roll, an arm projecting from the frame, and a rotary eccentric engaging with the free end of the arm and adapted to determine the normal position of the feed roll.

5. A skiving machine comprising a tubular 95 skiving knife, a feed roll, means for supporting the feed roll including a frame pivoted to rock about an axis extending transversely to the axis of rotation of the knife, and means for locating the feed roll in a predetermined operative position including 100 an eccentric member having an axis of rotation parallel to the rocking axis of the frame, and means for yieldingly retaining the frame in contact with the eccentric member.

6. A skiving machine having, in combination, 105 a tubular skiving knife, coöperating members located upon opposite sides of the knife for guiding and feeding the work to the knife, a grinding disk having its face positioned in operative relation to the outer surface of the knife, means for rotating the disk, means for moving the disk toward and from the knife, a second grinding disk having its face disposed in operative position to the inner surface of the knife and adapted to be rotated through contact with the knife, and means for normally moving the second disk toward the knife.

7. A skiving machine comprising a tubular 120 knife, a grinding disk disposed in operative relation to the outer surface of the knife, a pivoted arm supporting the disk, means for adjusting the disk angularly with respect to the arm, and means for rotating 125 the disk.

8. A skiving machine comprising a tubular 130 skiving knife, a grinding disk supported in operative relation to the outer surface of the knife, a head upon which the disk is

journaled, a pivoted arm, and adjustable connections between the head and arm adapted to permit adjustment of the head and grinding disk carried thereby about an axis passing substantially through the point of engagement of the grinding disk and the skiving knife.

9. A skiving machine comprising a tubular skiving knife, a feed roll normally located in close proximity to the knife edge, a head inclosing the knife and feed roll and including two hinged parts, a latch for locking the two parts of the head together, and means for moving the feed roll away from the knife edge when the latch is released.

10. A skiving machine comprising a tubular skiving knife, a feed roll normally positioned in close proximity to the knife edge,

a head inclosing the feed roll and knife and including two parts hinged together, and means under the control of the operator for bodily moving the feed roll away from the knife edge.

11. A skiving machine comprising a head having two hinged parts, a skiving knife mounted in one part of the head, a feed roll mounted in the coöperating part of the head, means for normally supporting the feed roll in close proximity to the knife, and means under the control of the operator for removing the feed roll from the knife edge to insure against engagement of the feed roll with the knife edge when the head is opened and closed.

ALBERT LATHAM.
